United States Patent

Des. 239,379

Patented Mar. 30, 1976

239,379

AUTOMOBILE WHEEL

John Siroonian, Fresno, Calif., assignor to Western
U.S. Industries, Fresno, Calif.

Filed Sept. 13, 1974, Ser. No. 505,937

Term of patent 14 years

Int. CL. D12—16

U.S. CL. D12—205

Fig. 2.

FIG. 3.

FIG. 4.

FIG. 1 is a front elevational view of an automobile wheel showing my new design;

FIG. 2 is a cross-sectional view thereof taken along line 2—2 in FIG. 1;

FIG. 3 is a rear elevational view thereof; and

FIG. 4 is a side elevational view thereof.

I claim:

The ornamental design for an automobile wheel, as shown.
